UNITED STATES PATENT OFFICE.

JAMES M. KELLER, OF LOS ANGELES, CALIFORNIA.

CONDENSER.

SPECIFICATION forming part of Letters Patent No. 784,685, dated March 14, 1905.

Application filed April 5, 1904. Serial No. 201,718.

To all whom it may concern:

Be it known that I, JAMES M. KELLER, a citizen of the United States, residing at Los Angeles, county of Los Angeles, State of California, have invented and discovered a new and useful Improvement in Attachments for Combined Feed-Water Heaters and Condensers; and I do hereby declare the following to be a full, clear, and exact description of the invention, such as will enable others skilled in the art to which it appertains to make and use the same.

My invention relates to improvements in attachments for combined feed-water heaters and condensers; and the objects of my improvement are, first, to construct an apparatus for quickly, conveniently, and economically condensing the feed-water to be supplied to boilers of engines, and, second, to purify the feed-water, reference being made to the accompanying drawings, to the figures, and the reference-numerals marked thereon.

The invention consists, essentially, in the construction, combination, and arrangement of the several parts, as will be hereinafter fully described in the specification, shown upon the drawings appended hereto, and specifically pointed out in the claims made a part hereof. I attain these objects by the construction and arrangement of the several parts illustrated in the accompanying drawings, in which—

Figure 1 is a view in elevation showing the several parts connected together. Fig. 2 is a plan view of the water and oil pipes located in the upper compartment of the casing removed therefrom. Fig. 3 is a longitudinal vertical sectional view taken on the line *a a* of Fig. 4, and Fig. 4 is a vertical cross-sectional view taken on the line *b b* of Fig. 3.

Similar reference-numerals refer to like parts throughout the several views.

The reference-numeral 1 denotes the casing inclosing parts of the apparatus, the partition-plates 2 2, the air-tubes 3 3, the oil-pipes 4 4, the feed-water pipes 5 5, the trap-plates 18 18 and 19 19, and the casing forming the receptacle 7 in the lower portion thereof for the water condensed from the steam admitted into the casing in the upper compartment 2' thereof.

The steam from the high and low pressure

engines 8 and 9, respectively, or from either of said engines when used singly is conveyed by the pipe 10 into the uppermost compartment 2' of the casing 1, and the steam circulates around the oil-pipes 4 4, which are U-shaped, one end of which being connected with an oil-supply tank or an oil-pump, (not necessary to be shown,) the other end of the said U-shaped oil-pipe leading to the fire-box of the engine employed for operating the plant. The oil in the said oil-pipes 4 4 is heated while passing through the said pipes by the exhaust-steam or otherwise, and when it reaches the said fire-box of the engine it is evaporized and the temperature of the oil has been elevated, thereby saving fuel in order to raise the oil to the combustion-point thereof. The feed-water in the feed-water pipes 5 5 in compartment 2' is also heated by the steam circulating around the same, the feed-water being forced through said pipes 5 5 by means of the feed-water pump 11 and is returned again to the said pump 11, together with the water brought into the casing 1 from the spray-pipes 12 12, connected to the water-supply system of the city or town where the plant is located. The flow of the water through the spray-pipes 12 12 into the casing 1 is regulated by means of the float 13, the rod 14, and the valve 15 within the pipe 12' on the outside of the casing 1. Whenever the water in the receptacle 7 in the lower portion of the casing 1 is decreased in quantity, the float 13 drops, the rod 14 descends and opens the valve 15, and the water from the said supply system passes through the spray-pipes 12 12 into the casing 1 until the requisite quantity of water has accumulated in the receptacle 7, when the float 13 again elevates the rod 14 and closes the valve 15 and stops the spray or water from entering the casing 1. The receptacle 7 in the lower portion of the casing 1 is connected with the cylinder 16, in which the float 13 is operated, on the outside of said casing 1 by means of the pipe 17, through which water in the receptacle 7 is conveyed into said cylinder. The exhaust-steam from the said engines passes from the compartment 2' in the top of the casing 1, first circulating around the said oil-pipes 4 4, then around the feed-

water pipes 5 5, and travels to the farther end of the casing 1 and falls over the end of the partition-plate 2 between the end thereof and the inner surface of the casing 1 through the 5 passage-way 6. From the compartment 2' the steam enters compartment 2'', travels to the opposite end of the partition-plate 2, separating the two uppermost compartments, and there circulates around the air-pipes 3 3, 10 located in said compartment 2''. From the compartment 2'' the steam condensed and the spray pass into compartment 2''', from thence into compartment 2''', from thence into compartment 2''', and from thence into compartment 2''', and from this last-mentioned compartment the condensed steam and spray fall over the end of the lowermost partition-plate 2, between the end thereof and the inner surface of the casing 1, through the passage-way 15 6, into the receptacle 7 in the lower portion of said casing.

To the lowermost partition-plate 2, on the under side thereof, depending vertically downward therefrom, I secure in any suitable manner downwardly-projecting trap-plates 18 18, and to the bottom of the casing 1 in the receptacle 7, projecting vertically upward, I secure in any suitable manner the trap-plates 19 19. The said trap-plates 18 18 and 19 19 20 in the receptacle 7 of the casing 1 form traps by means of which the oil taken up by the steam, used for lubricating portions of the piston, piston-head, and other parts of the engine, found mixed with the water condensed from the steam, is drawn off through a suitable overflow-pipe (not necessary to be shown) 25 from the surface of the water in the receptacle 7.

The casing 1 may be thoroughly washed out 40 by opening the valve 15 in the pipe 12' on the outside of the casing 1 and the valve 20 in the drain-pipes 22 22, connected to the bottom of the receptacle 7 on the outside thereof by means of the handle 21, thus permitting 45 the water from the said water system to flow through the casing.

The passage of the steam and vapor from the compartment 2' of the casing into and through all of the intermediate compartments 50 in a serpentine course into compartment 2''', and, lastly, into the receptacle 7 at the bottom of the casing 1, is augmented and materially hastened by means of my pneumatic apparatus, the air-pump 25, and pipe 26, leading from 55 the lower portion of the casing 1, preferably from the lowermost of said compartments—that immediately above the receptacle 7—to the said air-pump. By means of the said air-pump 25 and connecting-pipe 26 and the condensation of the steam a vacuum is created 60 in the casing, the capacity of the condenser greatly increased, the engine or engines relieved, and time and labor saved. By means of the fan or blower 30, operated by the engine 31, uncontaminated pure air is forced 65

through the air-pipes 3 3, located in the said compartment 2', to and including compartment 2''', heated by means of the exhaust-steam or condensed hot water from the exhaust-steam circulating around said air-pipes, 70 and emerges from the opposite ends of said air-pipes into the hood 33, located at the opposite end of the casing 1 from that to which the said fan or blower is attached. The pure heated air is conveyed from the hood 33 by 75 means of pipes, flues, or chutes to parts of the building in which the plant is located or may be carried to other buildings desired to be heated.

It is obvious that many variations and 80 changes in the details of construction and arrangement of my invention would readily suggest themselves to persons skilled in the art to which it appertains and still be within the scope and spirit of my improvement. 85

I do not desire to confine this invention to the specific construction, combination, and arrangement of parts herein shown and described, and the right is reserved to make all changes in and modifications of the same as 90 come within the spirit of this invention; but I do desire to secure as my invention all features of construction and equivalents thereof that come within the scope of my improvement as herein shown and described, and illustrated 95 upon the drawings appended hereto.

What I claim as my invention, and desire to secure by Letters Patent, is—

1. A feed-water heating and condensing apparatus comprising a casing having compartments, the partition-plates secured to the casing and arranged one above the other therein, the said partition-plates provided with passageways between alternate ends thereof and the inner face of the ends of the casing, a pipe 100 for conveying exhaust-steam from an engine to the casing, feed-water pipes, a pump for circulating the feed-water through the feed-water pipes, the spray-pipes for conveying cold water within the casing and an air-pump 105 for increasing the circulation of the condensed steam and water through the casing.

2. A combined feed-water heating and condensing apparatus, comprising a casing having compartments, the partition-plates secured to the casing at alternate ends thereof, the said partition-plates provided with passage-ways between alternate ends thereof and the inner face of the ends of the casing, a pipe for conveying exhaust-steam to the uppermost compartments of the casing, feed-water pipes and pump for continuously circulating the feed-water through the feed-water pipes within the casing, spray-pipes for conveying cold water within the casing and an air-pump for increasing the circulation of the condensed steam and water through the casing. 120

3. A combined feed-water heating and condensing apparatus, comprising a casing having compartments one arranged above the 125

other, the partition-plates secured to the casing at one end and provided with passage-ways between alternate ends thereof and the inner face of the ends of the casing, a pipe for conveying exhaust-steam to the upper portion of the casing, feed-water pipes located in said upper portion of the casing, a pump for continuously circulating the feed-water through the feed-water pipes within the casing and an air-pump for augmenting the circulation of the condensed steam and water through the casing.

4. A combined feed-water heating condensing and circulating apparatus, comprising a casing having compartments therein formed by partition-plates secured to the casing, feed-water pipes located in the uppermost compartments of the casing, means for continuously circulating the feed-water through the said feed-water pipes, a pipe for conveying exhaust-steam to the said uppermost compartment, spray-pipes for conveying cold water within the casing and a pump for increasing

5 10 15 20

the circulation of the condensed steam and water through the casing.

5. A combined air, feed-water heating and condensing apparatus, comprising a casing provided with partition-plates forming compartments within the casing, pipes for conveying air and feed-water through the casing, means for conveying exhaust-steam to the upper portion of the casing, spray-pipes for conducting cold water to the casing, means for forcing cold air through the air-pipes within the casing and an air-pump for increasing the circulation of condensed steam and water through the casing.

In testimony whereof I have signed my name to this specification in the presence of two subscribing witnesses.

JAMES M. KELLER.
